REDUCING INTERSYSTEM CROSS TALK BETWEEN CARRIER CHANNELS.

Application filed September 17, 1925. Serial No. 57,009.

This invention relates to multiplex transmission and more particularly to the reduction of crosstalk between multiplex carrier systems superposed on adjacent transmission systems.

In carrier transmission systems where a plurality of signaling channels are superposed upon the ordinary voice or other signaling channel by the use of carrier currents of different frequencies, crosstalk between channels on the same conductive system is prevented by the use of selecting devices which have a range of selectivity wide enough to permit the satisfactory transmission of all frequency components in the signal, and the various channels are spaced from each other so that a sufficient frequency interval exists between channels to permit the selecting devices to attain sufficient cut-off or attenuation to prevent effective inter-channel crosstalk.

When two or more conductive systems on the same pole line are used for carrier transmission, another problem arises due to the crosstalk between the channel having a given carrier frequency on one conductive system and the channel having the same carrier frequency on an adjacent conductive system. This is an aggravated crosstalk condition as compared with that encountered in ordinary voice transmission because the crosstalk becomes greater in magnitude as the frequency becomes higher. It has been proposed to reduce this type of crosstalk by so arranging the channels that all those channels transmitting in one direction will be in one frequency range, and all those transmitting in the opposite direction will be in another range, the channels in a given range on one transmission system being organized to transmit in the same direction as the corresponding channels in the same range in the case of an adjacent transmission system. With such an arrangement the crosstalk is reduced because the transmission producing the crosstalk at each portion of the circuit is of the same order of magnitude as the signal transmission in the adjacent circuit and therefore the induced crosstalk will be

much smaller than the direct transmission. 50

While a system employing this principle is workable if a sufficient amount of transmission and balancing work is done upon the line conductors, it becomes desirable to attain further reduction in crosstalk in order 55 to make the circuits economical. Now, the natural assumption would be, that if the channels are as closely spaced as the selective systems will permit, without undue crosstalk between adjacent channels on the same 60 pair, the method of reducing crosstalk just described would be the most effective possible. If an attempt were made, for example, to stagger the channel frequencies employed on one pair with respect to the channel frequencies employed upon an adjacent pair it would apparently be necessary to separate the channels on each pair by the width of the signal band in order to prevent a given channel on one pair from crosstalking on the 65 staggered channels of the adjacent pair 70 which lie just above and just below the first mentioned channel.

The present invention involves the discovery that the channels of one system may 75 be staggered with respect to those of another system, even when the channels are as closely spaced in each system as the selective devices employed will permit, without any material tendency for a channel on one circuit to crosstalk into the channels immediately above and below it on the adjacent circuit.

The invention will now be more fully understood from the following description 85 when read in connection with the accompanying drawing, Figures 1 and 3 of which are charts illustrating two forms of channel arrangements which may be employed in accordance with the present invention, 90 while Figs. 2 and 4 are schematic representations to indicate how the channel spacing systems of Figs. 1 and 3 respectively may be applied in cases where more than two pairs of conductors on the same pole line 95 are multiplexed.

As already pointed out, the separation between channels in a carrier system must

be material because the selecting devices employed do not have a rigidly sharp cut-off and this results in the presence of certain "dead space" between the individual channels of a multi-channel system. This dead space serves no useful purpose in the transmission of intelligence over that particular system, but as this dead space is usually of less width than the width of a signal band it would not appear to be possible to squeeze a signal band on an adjacent transmission pair into this dead space without causing the upper and lower frequencies of the band to crosstalk into the channels on each side of the dead space. There are certain factors, however, which when taken into consideration will permit this seemingly impossible thing to be done.

In the first place, in ordinary telephone transmission all frequencies within the voice band are not of equal importance nor are all frequencies in the band transmitted with the same volume. As a matter of fact, those frequencies in the voice range which represent the major portion of the total energy of the whole band are a relatively narrow range of frequencies below the middle of the band. The higher frequencies of the band, in particular, are of very small energy and therefore will be only capable in any case of producing extremely weak crosstalk. Furthermore, the ordinary telephone set is so designed that the transmitter is not equally efficient at all frequencies within the voice range, but, on the contrary, is much more efficient for frequencies in the neighborhood of the middle of the range than for frequencies on either edge of the band. This same thing holds true of the sensitivity of the telephone receiver. Consequently, ordinary telephone transmission involves the transmission of relatively large volumes of energy in the middle of the voice band and relatively small volumes of energy on each side thereof, this being due, as already stated, not only to the nature of speech itself but also to the frequency characteristics of the transmitting elements of the telephone circuit as ordinarily designed. At the receiving end the importance of the frequencies near the middle of the voice band is greatly increased by the use of a receiver whose efficiency is greater in this range.

Consequently, it is possible where several carrier telephone systems, for example, are operated upon adjacent pairs carried by the same pole line, to arrange the systems which are nearest together so that their frequency allocations are staggered with respect to each other, that is, so arranged that the maximum energies of all of the channels of one system fall in the dead spaces of the adjacent system or, at least, in portions of the bands of the adjacent system where they will be the least harmful.

Referring to the chart of Fig. 1, for example, such a representative staggering arrangement is illustrated. In the upper portion of the chart the small rectangles in line A represent the frequency bands of three channels transmitting from east to west and three corresponding channels transmitting from west to east upon one circuit. Similarly, the small rectangles in the line B represent the frequency bands for three channels transmitting east and three channels transmitting west on an adjacent pair. It will be observed that the middle parts of the frequency bands of the one pair correspond to the dead spaces between the bands of the other pair. Of course, if all frequencies within a particular band were transmitted with equal volume the frequencies at the upper and lower sides of each band of one pair would crosstalk into the lower part of the band just above in the case of the adjacent pair and into the upper part of the band just below in the case of the adjacent pair. The lower part of the chart, however, shows in curve form the approximate distribution of the energy in the speech bands of the various channels. It will be seen from these curves that the energy attains a peak at about the middle of the band, dropping off sharply towards the lower part of the band and somewhat less sharply towards the upper side of the band. If we take the band 2 transmitting from east to west in the case of the group A, for example, it will be found that the major portion of the energy of the band falls within the dead space between bands 1 and 2 transmitting east to west of the B group. It is this energy which tends to produce more serious crosstalk and this energy falls in the frequency spectrum at a point where the selecting devices on the adjacent circuit produce the greatest attenuation. Consequently, the crosstalk induced in the adjacent circuit by the peak portions of each signal band is greatly reduced, and while the reduction in the volume of the crosstalk induced by the energy of the upper and lower frequencies of the band is not so great, since these portions of the band involve but small volumes of energy in the first place, the crosstalk induced by them will not be serious in any event.

A further factor that insists in the workability of a frequency allocation of this type is the fact that the carrier frequency is suppressed at the transmitter. If the carrier frequency were transmitted it would lie at one edge of the band and the volume of the carrier energy is usually much greater than that of the signal band itself, so that the carrier frequency would interfere with a staggered band on an adjacent circuit. By suppressing the carrier, however, this difficulty is not encountered and the system be-

comes quite workable. In fact, the staggering of the corresponding channels on adjacent pairs reduces the effective crosstalk between the two systems to a very small fraction, ranging from two to ten per cent of the crosstalk that would exist if the two systems had identical frequency allocations.

Figure 2 shows how the frequency allocations may be made upon different pairs of conductors when more than two pairs of conductors on the same pole line are multiplexed. Here, the frequency allocation shown at A in Fig. 1 is employed for all of the even pairs while the B allocation is employed for all the odd pairs. By this arrangement the channels of a given pair are staggered with respect to the channels of the nearest adjacent pair on each side, while the channels of a given pair will coincide with the channels of the second pair at either side thereof. The second pairs are necessarily located at a greater distance than the immediately adjacent pairs so that the crosstalk in this case is cut down in volume by a special separation rather than by frequency separation. In other words, the crosstalk between immediately adjacent pairs will be greatly reduced by the staggering arrangements while the crosstalk between two systems of similar frequency allocation will be reduced by lack of proximity, the two systems being separated by an intermediate pair.

In ordinary telephone practice where phantoms are used it is, of course, customary to transpose the phantom, so that the pairs of the phantom group alternately change position. Under such conditions the advantages of the two different frequency allocations may be realized by assigning different allocations to pairs having high coefficients of crossinduction between one another, and like allocations to pairs having low coefficients of crossinduction between one another.

In some instances a staggering arrangement may be effectively provided using more than two frequency allocations. A system employing three degrees of staggering may be designed as indicated in Fig. 3. Here, the carrier frequency of the channels numbered 1 of systems B and C equally spaced between the carrier frequency of channels 1 and 2 of system A. With this arrangement the peaks of energy in the two channels of systems B and C fall between the peaks of energy of the two adjacent channels in system A. In this case, of course, the reduction in crosstalk between any two of the three frequency allocations will not be as great as in the double frequency allocation of Fig. 1. On the other hand, the additional pair combination which is made available by this system will, in its application to a number of systems on the same pole line, make it possible by staggering to reduce crosstalk in cases where one pair intervenes

between two circuits, one crosstalking into the other, as well as effecting a reduction in crosstalk between two immediately adjacent pairs.

Figure 4, of course, illustrates the frequency allocation employed for the various pairs on a pole line where more than three pairs are multiplexed. Frequency allocation A is used for the first and fourth pairs, frequency allocation B for the second and fifth pairs, frequency allocation C for the third and sixth pairs, etc.

It will be obvious that the general principles herein disclosed may be embodied in other and different forms without departing from the spirit and scope of the appended claims.

What is claimed is:

1. A transmission system in which a plurality of transmission circuits are extended along the same pole line, carrier channels superposed on each transmission circuit, the frequency bands of the channels on a particular circuit being only separated from each other by a sufficient range to prevent undue crosstalk from one channel to an adjacent channel on the same circuit, and the frequency bands of the channels of one circuit being so allocated with respect to the bands of the channels of the adjacent circuit that the portion of the band carrying the maximum energy will coincide with the separating range between the bands of the adjacent circuit. 85

2. A transmission system in which a plurality of transmission circuits are extended along the same pole line, a plurality of carrier channels superposed on each transmission circuit, the frequency bands of the various channels of each transmission circuit being separated by a frequency range of such width as to prevent undue crosstalk between any channel and an adjacent channel on the same circuit, said separating frequency range being of less width than the individual frequency bands themselves, and the frequency bands of one transmission circuit being so allocated with respect to those of the nearest adjacent circuit that the portion of the band carrying the maximum amount of energy will coincide with a range separating two bands on the adjacent circuit. 105

3. A transmission system comprising a plurality of transmission circuits, a plurality of signaling channels superposed upon each transmission circuit, the frequency bands corresponding to the various channels of each circuit being separated from each other only by a frequency range of sufficient width to prevent undue crosstalk between adjacent channels of the same circuit, and the frequency bands of the channels on any given transmission circuit being so allocated with respect to the bands of other circuits upon the same pole line that the parts of the 120

130

bands carrying the maximum energy upon the two nearest adjacent circuits on each side will fall within the range separating two of the bands of the first circuit, the bands of the two adjacent circuits being also so related that the portions thereof carrying the maximum energy will be offset with respect to each other.

4. A transmission system in which a plurality of transmission circuits are extended along the same pole line, carrier channels superposed on each transmission circuit, the frequency bands of the channels on a particular circuit being only separated from each other by a sufficient range to prevent undue crosstalk from one channel to an adjacent channel on the same circuit, and the frequency bands of the channels of one circuit being so allocated with respect to the bands of the channels of the adjacent circuit that the portion of the band carrying maximum energy will coincide with a part of the bands on the adjacent circuit which corresponds to a range in which the receiving element of the adjacent circuit is inefficient.

5. A transmission system in which a plurality of transmission circuits are extended along the same pole line, a plurality of carrier channels superposed on each transmission circuit, the frequency bands of the various channels of each transmission circuit being separated by a frequency range of such width as to prevent undue crosstalk between any channel and an adjacent channel on the same circuit, said separating frequency range being of less width than the individual frequency bands themselves, and the frequency bands of one transmission circuit being so allocated with respect to those of the nearest adjacent circuit that the portion of the band carrying maximum energy will coincide with a part of the bands on the adjacent circuit which corresponds to a range in which the receiving element of the adjacent circuit is inefficient.

6. A transmission system comprising a plurality of transmission circuits, a plurality of signaling channels superposed upon each transmission circuit, the frequency bands corresponding to the various channels of each circuit being separated from each other only by a frequency range of sufficient width to prevent undue crosstalk between adjacent channels of the same circuit, and the frequency bands of the channels on any given transmission circuit being so allocated with respect to the bands of other circuits upon the same pole line that the portions of the bands carrying maximum energy on the two nearest adjacent circuits on each side of given circuit will coincide with the part of the bands on the intermediate circuit which corresponds to a range in which the receiving element is inefficient, the bands of the two adjacent circuits being also so

related that the portions thereof carrying maximum energy will be offset with respect to each other.

7. A transmission system in which a plurality of transmission circuits are extended along the same pole line, carrier channels superposed on each transmission circuit, the frequency bands of the channels on a particular circuit being only separated from each other by a sufficient range to prevent undue crosstalk from one channel to an adjacent channel on the same circuit, and the frequency bands of the channels of one circuit being so allocated with respect to the bands of the channels of the adjacent circuit that the portion of the band carrying maximum energy does not coincide with the portion of the band on an adjacent circuit which carries maximum energy.

8. A transmission system in which a plurality of transmission circuits are extended along the same pole line, a plurality of carrier channels superposed on each transmission circuit, the frequency bands of the various channels of each transmission circuit being separated by a frequency range of such width as to prevent undue crosstalk between any channel and an adjacent channel on the same circuit, said separating frequency range being of less width than the individual frequency bands themselves, and the frequency bands of one transmission circuit being so allocated with respect to those of the nearest adjacent circuit that the portion of the band carrying maximum energy does not coincide with the portion of the band on an adjacent circuit which carries maximum energy.

9. A transmission system in which a plurality of transmission circuits are so related as to produce cross induction, carrier channels superposed upon each transmission circuit, the frequency bands of the channels of a particular circuit being only separated from each other by a sufficient range to prevent undue crosstalk from one channel to an adjacent channel on the same circuit, and the frequency bands of the channels of one circuit being so allocated with respect to the bands of the channels of a circuit having the highest coefficient of cross induction with respect to said circuit that the portion of the band carrying the maximum energy will coincide with the separating range between the bands of said other circuit.

10. A transmission system in which a plurality of transmission circuits are so related to each other that cross induction will result, a plurality of carrier channels superposed on each transmission circuit, the frequency bands of the various channels of each circuit being separated by a frequency range of such width as to prevent undue crosstalk on an adjacent channel of the same circuit, said separating frequency range being of less

width than the individual frequency bands themselves, and the frequency bands of one transmission circuit being so allocated with respect to those of the circuit having the highest coefficient of cross induction with respect thereto that the portion of the band carrying the maximum amount of energy will coincide with a range separating two bands on said other circuit.

In testimony whereof, I have signed my ¹⁰ name to this specification this 16th day of September, 1925.

HERMAN A. AFFEL.
